The ornamental design for a lozenge-shaped snack, as shown and described.

DESCRIPTION

FIG. 1 is a perspective view of a lozenge-shaped snack, showing my new design;

FIG. 2 is a right side view thereof;

FIG. 3 is a left side view thereof;

FIG. 4 is a view thereof, taken from above;

FIG. 5 is a view thereof, taken from below;

FIG. 6 is a front view thereof; and,

FIG. 7 is a rear view thereof.

The lozenge-shaped snack has a bulging and rugged aspect.
